(**) Term: **14 Years**

(57) **CLAIM**

(21) Appl. No.: **29/204,277**

The ornamental design for central processing unit module for programmable logic controller, as shown and described.

(22) Filed: **Apr. 28, 2004**

DESCRIPTION

(30) **Foreign Application Priority Data**

Nov. 10, 2003 (KR) 30-2003-0031741

FIG. 1 is a perspective view of central processing unit module for programmable logic controller showing the new design:

(51) **LOC (8) Cl.** **14-02**

FIG. 2 is a front view thereof;

(52) **U.S. Cl.** **D14/301**

FIG. 3 is a rear view thereof;

(58) **Field of Classification Search** D14/300–302,

D14/308, 311; D13/162, 184, 199, 99.01–99.12;

369/34.01, 36.01; 361/680–686, 690–696

FIG. 4 is a left-side view thereof;

See application file for complete search history.

FIG. 5 is a right-side view thereof;

(56) **References Cited**

FIG. 6 is a top plan view thereof; and,

U.S. PATENT DOCUMENTS

FIG. 7 is a bottom plan view thereof.
